UNITED STATES PATENT OFFICE.

JOHN HARRY WELLS, OF BOSTON, MASSACHUSETTS, ASSIGNOR TO MULTISIZE ROTARY PRESS CO., LIMITED, OF TORONTO, CANADA.

VARIABLE-SPEED MECHANISM.

Application filed February 5, 1925, Serial No. 7,028, and in Canada February 4, 1925.

This invention relates to variable speed mechanism adapted for use in imparting motion to the cylinders of a printing press adapted for printing, without waste of paper, many different sizes of work. The invention is also adapted for driving cutters, perforators, scorers, folders or creasers and the like.

When used in connection with a press the desired result is attained by employing two printing cylinders, with their accessories, and each provided with a printing plate subtending an arc less than a full circle, one printing the blank spaces on the web of paper left by the other; and by providing mechanism whereby each cylinder is rotated at a constant speed while printing and at a different speed while not printing so that the cylinders each rotate through the printing arc of their peripheries in the same time that they rotate through the non-printing arc of their peripheries. It will be distinctly understood that more than two printing cylinders may be used and that one cylinder will print the blank spaces left by the other cylinders or one cylinder may be used for printing a certain colour while one or more other colours are superimposed on the first impression.

If the printing plates on the cylinders subtend an arc of less than 180° it is evident that the "different" motion above referred to must be an accelerated motion, while if the plates subtend an arc of over 180° the "different" motion must be a retarded motion. It is also evident that, if the press is to be adapted for many different lengths of printing plates to suit different lengths of printed sheets, means must be provided to vary the length of the arc of constant or printing speed and for varying the speed during the non-printing periods according to the length of the non-printing arc of each cylinder. It is also essential that the speed during the making of any one impression should be as nearly absolutely constant as possible and should not vary in such a manner as to affect the registration of the printing cylinders. My object therefore is to devise variable speed mechanism for printing presses and the like which will enable a very wide range of sizes to be printed, which is easily adjusted to print any desired size within its range, which will effect

the changes from constant to "different" speed with as little shock and jar as possible, in which the speed-varying mechanism is so locked during the periods of constant speed that it cannot have any effect in producing any irregularity in the speed, and thus in the printing, in which means are provided for attaining substantially perfect meshing of the interchangeable gears used in varying the length of the printing arc, in which the periods of constant speed and "different" speed are delimited with substantially absolute accuracy, and which is rugged and not liable to lose accuracy by wear.

I attain my object by means of the constructions hereinafter described and illustrated in the accompanying drawings in which—

Fig. 1 is a longitudinal section of my variable speed mechanism showing it connected with a printing press;

Fig. 2 a plan view, partly in horizontal section, of the two carrying members and rear change gears shown in Fig. 1;

Fig. 3 a section on the line 3—3 in Fig. 1 showing, in full lines, an end elevation of the speed-varying member in its position at the commencement of its rotary movement and showing, in constructional lines, its position at the end of its rotary movement;

Fig. 4 a section on the line 4—4 in Fig. 1 showing an end elevation of the gear part of the carrying member and part of the second carrying member after they have been revolved a portion of a revolution and showing the speed-varying member in its position at the end of its rotary movement;

Fig. 5 a front elevation of the casing for my mechanism showing the gear carrying frame and the mechanism for finely adjusting it;

Fig. 6 an underside plan view of the fine adjustment mechanism shown in Fig. 5;

Fig. 7 a section on the line 7—7 in Fig. 1 showing an end elevation of the parts of my variable speed mechanism and showing the rear gearing employed to attain one direction of rotation of the rotary driven member; and

Fig. 8 a diagrammatic view of the rear gearing showing a different arrangement of gears, to reverse the direction of rotation of the rotary driven member and to reduce its speed, from that shown in Fig. 7.

In the drawings like numerals of reference indicate corresponding parts in the different figures.

- 1 is a constant speed shaft journalled at 5 its forward and rear ends in bearings 2 and 3 respectively, which are carried by a housing or casing 4 adapted to enclose the parts of the mechanism hereinafter described. 5 is a rotary driven member formed as a sleeve 10 loosely mounted on the constant speed shaft 1. It is the function of the apparatus or mechanism as a whole to actuate this rotary member 5 at the same speed as the shaft 1 for a portion of each revolution and at a varied speed during the remainder of each revolution. This rotary driven member, by means of any suitable gearing such as 6, may be used to actuate any desired mechanism or machine such, for example, as the cylinder 20 or cylinders of a printing press.
- The driving connection between the constant speed shaft and the rotary driven member is provided by the following mechanism. On the shaft 1 is secured a carrying member comprising a gear 7 and a disk 7^a. This gear is meshed with a pinion 7^f secured to a countershaft which is detachably connected, by means of a clutch (not shown), with a driving shaft of the printing press. 25 The disk is spaced from the gear and connected therewith by means of shouldered studs 7^b (see Fig. 1) adapted to maintain the disk and gear in spaced relationship. A spindle 7^c, journalled eccentric to the shaft 1 in the carrying member, has at its outer end, a speed-varying member 8 connected thereto, the inner end of the spindle being splined to removably carry a change gear 7^d. Preferably the spindle is journalled in a 30 bushing 7^e carried by the gear 7 and disk 7^a, the bushing having a shoulder formed at one end for engagement with the gear and having a nut threaded on the opposite end, adjacent the spline, for engagement with the disk. The bushing thus also serves to hold the parts together and prevents any bending stresses acting on the spindle. 35 The rotary driven member 5 has gears B¹ and C¹ suitably secured thereto the former gear meshes with a gear B², of substantially the same number of teeth as the gear B¹, see Figs. 1, 2 and 7. The gear B² is secured to a spindle B³ journalled in a second carrying member which comprises a pair of spaced disks B⁴ and B⁵ connected by shouldered studs B⁸. These disks are located between the gear 7 and disk 7^a and are rotatably mounted on the hubs of the latter so that they may be rotarily adjusted relative to the gear and disk, as hereinafter described. On the inner face of the disk B⁵ are formed two hubs B⁶ and C⁶ which are diametrically opposite one another and pass through arcuate slots B⁷ and C⁷ formed in the disk 7^a. One 40 end of the spindle B³ passes through the hub

B⁶ and is journalled therein, the inner end of the spindle being splined so that a gear B may be removably secured thereto. This gear is adapted to mesh with an idler gear D carried on an arm D¹ which is rotarily adjustable relative to the first or second mentioned carrying members by means of the bolt and slot connections D² between the arm and the disk 7^a. The gear D is adapted to mesh with the gear 7^d by which it is driven.

The studs B⁸ are provided with shoulders to maintain the disks B⁴ and B⁵ in spaced relationship. One or more clamps 9 are provided for releasably locking these disks after they have been rotarily adjusted to mesh the gear B with the gear D. Each clamp comprises a pair of sleeves, mounted on a stud 7^b and adapted to engage the adjacent faces of the disks B⁴ and B⁵, and a lever suitably carried by the bolt in engagement with one sleeve. The lever has an eccentric end adapted to engage the other sleeve whereby the gear 7 and disk 7^a of the first mentioned carrying member may be forced slightly farther apart.

It is evident that if the spindle 7^c be held from rotation relative to the carrying member that the rotary driven member will be actuated at the same speed as the constant speed shaft 1 whereas if the spindle 7^c be rotated on its axis at various speeds that the rotary member will be actuated at varied speeds either faster or slower than the constant speed of the shaft 1, depending on whether the rotary movement of the speed-varying member is added to or subtracted from the movement of the rotary driven member.

I will now describe the manner in which the spindle 7^c is intermittently rotated during a portion of the revolution of the constant speed shaft 1. The speed varying member 8 is formed as a hub secured to the spindle 7^c and has a plurality of ratchet teeth 10 formed on its periphery, see Figs. 3 and 4. In the drawings there are four equally spaced teeth shown which are adapted to be engaged seriatim by a spring actuated pawl 11 pivoted on an oscillatable member 12 journalled on the member 8. Preferably there are two diametrically opposite pawls 11 employed for engaging two of the teeth 10 at the same time to equalize the load on opposite sides of the spindle 7^c. The oscillatable member is provided with a laterally extending projection 12^a having an anti-friction roller thereon for engagement with a cam groove formed in the side of a cam disk 14. This cam is adapted to oscillate the member 12 to cause the pawls to partially rotate the speed varying member and to return the pawls to their starting position for engagement with the next pair of ratchet teeth on the next revolution of the

constant speed shaft. In Fig. 3 the starting and finishing positions of the speed varying and oscillatable members are shown in full and in construction lines respectively, 5 and it will be noted that the rotary movement imparted to the spindle 7^e takes place during a portion less than half of a revolution of the constant speed shaft 1. The speed of the rotary driven member 5 is thus 10 varied relative to the speed of the constant speed shaft for a portion of a revolution and the two rotate together for the remainder or more than half of the revolution.

The cam 14 is mounted on a sleeve journaled on the shaft 1 and is geared thereto so that its speed and its direction of rotation may be varied relative to the speed and direction of rotation of the constant speed shaft 1, see Figs. 1 and 5. The forward or 20 outer end of the shaft 1 is splined and on this spline is removably carried a gear 14^a which meshes with an idler gear 14^b carried on a frame 15. This frame, hereinafter more fully described, is provided with a 25 split hub carried on an extension formed on or carried by the bearing 2 so that it may be swung concentric to the shaft 1. A screw 16 is provided for clamping the split hub to the bushing after the frame has been rotationally adjusted to bring the gear 14^b into mesh with a gear 14^c which is removably secured on a shaft 14^d. This shaft is journaled in the casing 4 and has a pinion 14^e secured thereto, which pinion is constantly 30 in mesh with a gear 14^f formed on or secured to the cam 14. By changing the size of the gears 14^a, 14^b or 14^c the speed of the cam will be varied and by using two idler gears 14^b instead of one the direction of rotation 35 of the cam will be changed from the direction indicated in Fig. 5.

The rotary driven member 5 is detachably connected with the machine which it actuates as follows. The gearing 6 (see Fig. 1) 40 includes a gear 6^a journalled on the shaft 1 and adapted, by means of a clutch member 6^b secured to the rotary driven member 5, to be driven by the latter. The gear is provided with a circular T slot arranged concentrically of the axis of the shaft and adapted to receive a plurality of T headed bolts 6^c carried by the member 6^b. The bolts are provided with nuts adapted, when drawn up tightly against the face of the member, to cause the T-heads to grip the gear and rotate the member and gear as a unit. The drawings show the gearing 6 connected with a printing cylinder 17 which is geared to an impression cylinder 17^a of an 45 ordinary rotary printing press. The cylinder 17 is provided with a printing plate 17^b which has the same radius as the radius of the impression cylinder 17^a and when the press is working under normal conditions, 50 that is without the use of the variable speed

mechanism, the printing and the impression cylinders are of the same circumference and their surface speed is equal at all times to the speed of the paper passing between them. Under these ordinary conditions the circumference of the impression cylinder governs 70 the length of the sheet of paper being used even if the plate does not extend all the way round the plate cylinder.

The variable speed mechanism hereinbefore described with the gearing shown in Figs. 1, 5 and 7 is adapted to accelerate the speed of the rotary driven member and thus the printing cylinder 17, relative to the speed of the shaft 1, during a portion of the 80 revolution of the printing cylinder, whereby a length of paper less than the circumference of the impression cylinder may be printed, without wasting any paper. This, of course, necessitates the use of a printing 85 plate subtending an arc less than that of the circumference of the cylinder so that the paper will pass freely at its uniform speed between the impression and printing cylinders while their speeds are being varied. 90 The length of the arc of the printing plate is substantially one-half the length of the desired length of papers so that by using two sets of similar printing cylinders actuated by the gearing 6 and by suitably carrying the paper round spacing rollers (not shown) the whole surface of the paper may be printed, one-half on one set of cylinders and the other half on the other set. By adjusting the position of the plates relative to 95 one another, two or more colored impressions may be superimposed on various lengths of paper.

It is evident that by changing the gear ratio or the direction of rotation between the 100 constant speed shaft 1 and the cam 14 and between the spindle 7^e and the rotary driven member 5 the length of the arc for varying the speed of the rotary driven member will be varied. The length of the arc of uniform speed of the printing cylinder 17 is thus varied and these variable periods control the number of different sized printing plates that may be used and thus the number of different sized sheets that may be 110 printed.

When it is desired to print from plates subtending an arc of more than 180° it is necessary to retard the speed of the rotary driven member, relative to the constant speed of the shaft 1, during the portion of its revolution in which the printing plate is free of the paper. This is accomplished by using two gears 14^b to change the direction of rotation of the cam 14 and omitting the gear D to cause the speed of the rotary member 5 to be subtracted from the speed of the shaft 1 and also by changing the gear ratios of the forward and rear drive gears, which are all removably carried on the spindles 125 130

and shafts so that they may be readily removed. It will be noted that the disk 7^a is provided with a splined stud adapted to carry a counterweight 18 to counterbalance the weight of the gear 7^a and that the hub C^a carries a spindle C^a adapted to carry a counterweight 19 to counterbalance the weight of the gear B. The arm D¹ is weighted at D^a to counterbalance the weight of the gear D and when this gear is dropped out of the gear train, formed by the gears 7^a, B, B² and B¹ to retard the speed of the rotary driven member 5, the arm D¹ is swung to and suitably secured to the right hand side of the gear 7^a instead of the position shown in Fig. 7. While the arm is in its inoperative position a counterweight (not shown) is substituted for the gear D¹ so that the weight D^a will be counterbalanced. The gear 7 and disk 7^a are also weighted on the side opposite the spindle 7^a to counterbalance the weight of this spindle, the bushing 7^a, speed-varying member 8 and the oscillatable member 12.

In printing from plates having certain lengths of arcs which only require a small acceleration or retardation of the rotary driven member 5 it would be necessary to use very large gears to obtain the required gear ratio between the intermittently rotated spindle 7^a and the rotary driven member 5. To overcome this objectionable feature I provide a second gear train, between the said spindle and rotary member, which may be substituted for the one hereinbefore described which includes the gears B, B¹ and B². A gear C¹ (see Figs 1, 2 and 8) secured to or formed integrally with the gear B¹ meshes with a pinion C² formed on or secured to the spindle C^a. The ratio of this pinion and gear is substantially one to four while the ratio between the gears B and B² is substantially one to one. A gear C is substituted for the counterweight 19 on the spindle C^a and this gear may be meshed with the gear D or with the gear 7^a depending on whether the printed sheet is to be shorter or longer than a normal sheet, the length of which, as hereinbefore mentioned, is equal to the circumference of the impression cylinder 17^a. When the gear C is in use the spindle B^a is provided with a counterweight 20 adapted to counterbalance the weight of the gear. The cam disk 14 is also counterbalanced.

The lower part of the casing 4 is shaped to form an oil sump into which all or some of the gears of each gear train will dip. The rear upper half 4^a of the casing is hinged at the back that it may be swung back to enable the rear change gears to be readily reached.

It is desirable to provide means to ensure that the removable gears in the forward and rear gear trains will be properly meshed

each time after they have been changed. This is accomplished on the forward gear train by providing a fine adjustment mechanism for actuating the gear carrying frame 15, see Figs. 5 and 6. This mechanism comprises a fulcrum stud 21 journaled in the end 4^b of the casing 4, and a slide 22 which is transversely movable on the stud. The upper end of the stud is cut away to form a projection 21^a having parallel sides adapted to be received in a slot formed in the slide. To one end of the slide is secured a yoke 23 which is pivotally connected, by a pin 24, with the frame 15. The other end of the slide is provided with a collar 27 in which is journaled one end of a screw 25 which is threaded through the stud. The other end of the screw is passed through the yoke and a pair of collars 26 are secured to the screw, one at each side of the yoke to prevent axial movement of the screw relative to the latter. The end of the screw adjacent the collar 27 is provided with a suitable hand wheel adapted when turned to actuate the slide and thus swing the frame 15 on its bearing when the clamp screw 16 is loosened. One end of the projection 21^a is cut to form an indicator (which may be a mark or a surface against which a straight edge may be placed) adapted to be alined with any one of the markings of a scale 26 formed on the slide. Each marking of the scale indicates where the indicator is to be positioned for a certain sized sheet of printing so that when the correct gears 14^a, and 14^c are secured on their shafts and the correct gear or gears 14^b are secured in the frame 15 and the handwheel operated to bring the desired marking into register with the indicator on the stud, the gears will be accurately meshed. The gears 14^b are journaled on a T-headed stud adapted to be received in a T or undercut groove 27 formed in the frame 15. This stud is adapted to be clamped as adjusted in any suitable manner in the groove. The frame 15 is provided with the clamping bolts 15^a and 15^b to assist the clamp 16 in holding the frame as adjusted.

To ensure the rear change gears B or C, carried on the second carrying member formed by the disks B⁴ and B⁵, are properly meshed with either the gear 7^a or D, the disk B⁴ is provided with spring actuated plungers 28 adapted to be received in the two concentric series of holes 29 formed in the gear 7 of the first carrying member. These holes are marked similar to the scale 26 to indicate which one is to be used for each setting so that the second carrying member may be rotarily adjusted and locked in its correct position relative to the first carrying member. The clamp 9, hereinbefore described, is used to take most of the strain off the plunger.

The constant speed shaft 1 is located, on the frame 17^e of the printing press, relative to the printing cylinders 17 and 17^a as follows. The press frame is provided with 5 a laterally extending boss, or large dowel 17^a adapted to be received in the inner end of the bearing 3 which projects beyond the end of the shaft 1.

While the speed-varying member 8 is being 10 carried through the arc in which all the parts of the mechanism travel at a uniform speed, it is desirable to positively lock the member 8 to prevent the rotary driven member 5 moving relative to the constant speed shaft 15. In the drawings the cam 14 is designed to actuate the speed-varying member a one-quarter revolution during each revolution 20 of the carrying-member 7, 7^a but variations of this arc of movement might be employed by changing the shape of the cam to increase or decrease the arc of the speed-varying member and by changing the gear ratios to correspond. In any case, to obtain good 25 printing results it is necessary to control the movement of the speed-varying member for substantially its whole rotary movement and then lock it as mentioned above. This is accomplished by securing a control cam 14^g to the cam 14 (see Figs. 1, 3 and 4), by 30 mounting both on a short sleeve and providing the speed-varying member 8 with four equally spaced projections carrying anti-friction rollers 8^a, 8^b, 8^c and 8^d adapted to engage the control cam. The control cam is 35 concentric to the cam 14 and the major portion of its periphery is concentric to the shaft 1. Referring particularly to Fig. 3, it will be seen that at the commencement of the 40 rotary movement of the speed-varying member, shown in full lines, the rollers 8^b and 8^c are contacting with or engaging the concentric portion of the control cam. As the carrying member 7, 7^a rotates past the cam 14, the projection 12^a on the oscillatable member 45 is swung away from the shaft 1 to impart the rotary movement to the speed-varying member. The roller 8^b is thus swung away from the control cam and the roller 8^c travels in towards the center of the control 50 cam which is shaped to engage this roller during this portion of the movement. As the rotary movement of the speed varying member progresses the member is partially turned on the spindle 7^e and the control cam 55 is provided with a low spot 14^h adapted to engage the roller 8^c during substantially the whole of its movement when the spindle 7^e is changing from its position behind this roller to its position in front of the roller. 60 The roller 8^c then substantially follows the contour of the control cam while the rotary movement is being completed to swing the roller 8^d into engagement with the concentric portion of the cam. When this happens 65 the roller 8^c has also moved sufficiently to

engage the concentric portion of the cam, as indicated in construction lines. These two rollers remain in engagement with the control cam, during the remainder of the revolution of the carrying member. From this it 70 is obvious that the relative position of the speed-varying and the oscillatable members will be controlled by the roller 8^c to tend to prevent the former member overrunning the second. It is also evident that the engagement of the rollers 8^c and 8^d, with the control cam, will positively lock the speed varying member from rotation when it is not being moved by the oscillatable member. During 75 the remainder of the revolution, in which the parts travel at uniform speed, the cam 14 returns the projection 12^a to its initial position whereby the pawls 11 will engage a fresh pair of teeth 10 in the member 8 to again actuate the latter on the next revolution 80 of the shaft 1. The roller 8^a will follow the contour of the cam 14^g on this next revolution and the rollers 8^a and 8^d will lock the member 8 during the period of 85 uniform speed. 90

With the above described controlling and locking mechanism the apparatus will actuate the printing cylinders to accurately register and is thus adapted for high-class work in producing two or more colors on various 95 sized sheets of paper.

To prevent the inturning roller on the speed-varying member 8 from forcibly striking the control cam at the end of its 100 rotary movement I provide means for checking the momentum of the member to positively prevent it from overrunning the pawl and ratchet drive connection 11 and 10 (see Figs. 3 and 4.) These means comprise a pawl 30 carried by the oscillatable member 105 12 for engaging any one of four equally spaced ratchet teeth 31 formed in the speed-varying member 8. The teeth 31 are formed in the opposite direction to the teeth 10 so that the pawl 30 will retain the driving engagement between the pawls 11 and the teeth 10 during substantially the complete 110 rotary movement of the speed-varying member. Preferably the pawl 30 is formed as a lever fulcrumed intermediate its ends and 115 is provided with an anti-friction roller 32, adapted to engage an arc shaped shoulder formed in the oscillatable member, to take the thrust. During the return movement of the oscillatable member it is necessary to disengage the pawl 30 from the speed-varying member to permit the former member to rock relative to the latter. For this purpose a finger 33 is provided which is carried on 120 a rod journaled in the member 12 and adapted to engage a pair of spaced shoulders formed on the end of the pawl. The rod has an arm 34 secured thereto, which arm is adapted to be rocked in one direction by a 125 projection 35 adjustably carried on the gear 130

7 to cause the finger to disengage the pawl 30 from its tooth 31. The arm 34 is adapted to engage a second projection 35 also adjustably carried by the gear 7 to cause the finger to be rocked in the opposite direction to move the pawl into engagement with a fresh tooth 31. The pawl is disengaged at or about the time the rotary movement of the speed-varying member ceases and is engaged at or about the time this rotary movement commences. The arm is provided with two flats either one of which will be engaged by a flat spring 36, carried on the member 12, to releasably retain the arm and thus the pawl as positioned.

The mode of operation is as follows. The clutch (not shown) connected with the countershaft to which the pinion 7¹ is secured, is thrown in to cause the pinion to drive the gear 7 and the disk 7^a which is connected thereto. The clutch 6^b is then tightened to form a driving connection between the rotary driven member 5 and the driving gears 6 only one of which is shown. The rotation of the gear 7 causes the constant speed shaft 1 to be driven which drives, by means of the forward change speed gears, the cam disk 14. As the first carrying member, formed by the gear 7 and disk 7^a, is rotated the spindle 7^c, gear 7^d, speed-varying member 8 and the oscillatable member 12 are revolved on the axis of the carrying member which moves at a different speed to the cam 14 to cause the member 12 to actuate the member 8 during a portion of each revolution as hereinbefore described. The second carrying member B⁴, B⁵ is rotated by means of the clamp 9 and plunger 28 with the first carrying member to cause the gear B or C, whichever one is being used, to revolve on the axis of the carrying member. The gear D, when used, also revolves on its axis as the arm D¹ is secured to the disk 7^a. From this it follows that during the portion of the revolution in which the oscillatable member is not actuating the speed varying member, the whole apparatus revolves with the constant speed shaft 1 at the impression speed and during the remainder of the revolution the oscillatable member causes the speed of the rotary driven member 5 to be varied relative to the speed of the shaft 1, this might be termed the recovering speed.

55 What I claim is:—

1. In variable speed mechanism for printing presses, the combination of a rotary driven member from which printing cylinders may be driven; means for driving the rotary driven member at a uniform speed during part of a revolution and at a different speed during the remainder of the revolution including an intermittently actuated rotary speed-varying member; means for positively locking said speed-varying mem-

ber when it is not in rotation, including a cam about which the speed varying member rotates and a plurality of rollers on the speed varying member, pairs of which consecutively engage the said cam during the periods of uniform speed; and means for varying the length of the arc of uniform speed without varying the speed which remains relatively constant for all settings of the device.

2. In variable speed mechanism, the combination of a constant speed shaft; a rotary driven member loose on the said shaft; a carrying member secured to said shaft; a spindle journaled in said carrying member; a rotary speed-varying member secured to said spindle; a rotatable member adapted to intermittently rotate said speed-varying member; means for positively locking said speed-varying member when it is not in rotation, including a cam about which the speed varying member rotates and a plurality of rollers on the speed varying member, pairs of which consecutively engage the said cam during the periods of uniform speed; and means for actuating said rotatable member at a predetermined speed relative to the constant speed shaft.

3. In variable speed mechanism, the combination of a rotary driven member; a carrying member rotatably mounted; a speed-varying member journaled on said carrying member eccentric to the axis thereof; gearing between said speed-varying member and the driven member; a cam disk adjacent the carrying member; means for rotating the carrying member and for imparting a relative movement of rotation to the cam disk and carrying member; an oscillatable member journaled concentric with the speed-varying member and actuatable by said cam; pawl and ratchet driving means whereby a stepwise rotary movement may be imparted to the speed-varying member by the rocking of the oscillatable member; and means for positively locking said speed-varying member while the said speed varying member is not being moved by the oscillatable member.

4. In variable speed mechanism the combination of a rotary driven member; a carrying member rotatably mounted; a speed-varying member journaled on said carrying member eccentric to the axis thereof; gearing between said speed-varying member and the driven member; a cam disk adjacent the carrying member; means for rotating the carrying member and for imparting a relative movement of rotation to the cam disk and carrying member; an oscillatable member journaled concentric with the speed-varying member and actuatable by said cam; pawl and ratchet driving means whereby a stepwise rotary movement may be imparted to the speed-varying member by the rocking of the oscillatable member; a plurality of

equally spaced projections on the speed-varying member; and a cam concentric with the first mentioned cam and engageable substantially continuously by two of said projections while the said speed-varying member is not being moved by the oscillatable member and thereby lock said member from rotation.

5. In variable speed mechanism, the combination of a rotary driven member; a carrying member rotatably mounted; a speed-varying member journalled on said carrying member eccentric to the axis thereof; gearing between said speed-varying member and the driven member; a cam disk adjacent the carrying member; means for rotating the carrying member and for imparting a relative movement of rotation to the cam disk and carrying member; an oscillatable member journalled concentric with the speed varying member and actuatable by said cam; a pawl and ratchet-driving means whereby a stepwise rotary movement may be imparted to the speed-varying member by the rocking of the oscillatable member; a plurality of equally spaced projections on the speed-varying member; and a cam concentric with the first mentioned cam and engageable substantially continuously by two of said projections while the said speed-varying member is not being moved by the oscillatable member and thereby lock said member from rotation, and having a low spot adapted for the passage of said projections one-by-one to permit of the movement of the speed-varying member by the oscillatable member and prevent overrunning of the said member.

6. In variable speed mechanism the combination of a rotary driven member; a carrying member rotatably mounted; a speed-varying member journalled on said carrying member eccentric to the axis thereof; gearing between said speed-varying member and the driven member; a cam disk adjacent the carrying member; means for rotating the carrying member and for imparting a relative movement of rotation to the cam disk and carrying member; an oscillatable member journalled concentric with the speed-varying member and actuatable by said cam; pawl and ratchet driving means whereby a stepwise rotary movement may be imparted to the speed-varying member by the rocking of the oscillatable member; a plurality of equally spaced projections on the speed-varying member; and a cam concentric with the first mentioned cam and engageable substantially continuously by two of said projections while the said speed-varying member is not being moved by the oscillatable member and thereby lock said member from rotation, and having a low spot adapted for the passage of said projections one-by-one to permit of the movement of the speed-

varying member by the oscillatable member and prevent overrunning of the said member, said cam being figured so that one projection is substantially always in contact with the cam surface.

7. A variable speed mechanism constructed as set forth in claim 4 in which the rotary speed-varying member is formed with four ratchet teeth and four projections and the oscillatable member with two pawls adapted to engage the teeth.

8. In variable speed mechanism, the combination of a rotary driven member; a carrying member rotatably mounted; a speed-varying member journalled on said carrying member eccentric to the axis thereof; gearing between said speed-varying member and the driven member; a cam disk adjacent the carrying member; means for rotating the carrying member and for imparting a relative movement of rotation to the cam disk and carrying member; an oscillatable member journalled concentric with the speed varying member and actuatable by said cam; pawl and ratchet-driving means whereby a stepwise rotary movement may be imparted to the speed-varying member by the rocking of the oscillatable member; a plurality of equally spaced projections on the speed-varying member; and a cam concentric with the first mentioned cam and engageable substantially continuously by two of said projections while the said speed-varying member is not being moved by the oscillatable member; pawl and ratchet mechanism between the speed-varying member and the oscillatable member adapted to check the momentum of the speed-varying member to prevent it over-running the pawl-and-ratchet drive; and means on the carrying member for engaging said retaining ratchet to throw it out of engagement at or about the time the rotary movement of the speed-varying member ceases.

9. In variable speed mechanism, the combination of a rotary driven member; a carrying member rotatably mounted; a speed-varying member journalled on said carrying member eccentric to the axis thereof; gearing between said speed-varying member and the driven member; a cam disk adjacent the carrying member; means for rotating the carrying member and for imparting a relative movement of rotation to the cam disk and carrying member; an oscillatable member journalled concentric with the speed varying member and actuatable by said cam; pawl and ratchet-driving means whereby a stepwise rotary movement may be imparted to the speed-varying member by the rocking of the oscillatable member; a plurality of equally spaced projections on the speed-varying member; and a cam concentric with the first mentioned cam and engageable substantially continuously by two of said projections while the said speed-varying member is not being moved by the oscillatable member and thereby lock said member from rotation, and having a low spot adapted for the passage of said projections one-by-one to permit of the movement of the speed-varying member by the oscillatable member and prevent overrunning the pawl-and-ratchet drive.

10. In variable speed mechanism, the combination of a constant speed shaft; a rotary driven member; a carrying member secured to said shaft; a rotary speed-varying member journalled in said carrying member; gearing between said speed-varying member and the driven member; a cam disk journalled concentric with the constant speed shaft and geared thereto; an oscillatable member pivoted concentric with the speed varying member and actuatable by said cam; pawl-and-ratchet driving means whereby a stepwise rotary movement may be imparted to the speed-varying means by rocking the oscillatable member; a plurality of equally spaced projections on the speed-varying member; and a cam concentric with the first mentioned cam and engageable substantially continuously by two of said projections while the said speed-varying member is not being moved by the oscillatable member and thereby lock said member from rotation.
11. In variable speed mechanism, the combination of a constant speed shaft; a rotary driven member; a carrying member secured to said shaft; a rotary speed-varying member journalled in said carrying member; gearing between said speed-varying member and the driven member; a cam disk journalled concentric with the constant speed shaft and geared thereto; an oscillatable member pivoted concentric with the speed-varying member and actuatable by said cam; pawl-and-ratchet driving means whereby a stepwise rotary movement may be imparted to the speed-varying means by rocking the oscillatable member; a plurality of equally spaced projections on the speed-varying member; and a cam concentric with the first mentioned cam and engageable substantially continuously by two of said projections while the said speed-varying member is not being moved by the oscillatable member and thereby lock said member from rotation, and having a low spot adapted for the passage of said projections one-by-one to permit of the rotary movement of the speed-varying member by the oscillatable member and prevent overrunning of the said member.
12. In variable speed mechanism, the combination of a constant speed shaft; a rotary driven member; a carrying member secured to said shaft; a rotary speed-varying member journalled in said carrying member; gearing between said speed-varying member and the driven member; a cam disk journalled concentric with the constant speed shaft and geared thereto; an oscillatable member pivoted concentric with the speed varying member and actuatable by said cam; pawl-and-ratchet driving means whereby a stepwise rotary movement may be imparted to the speed-varying member by rocking the oscillatable member; a plurality of equally spaced projections on the speed-varying member; and a cam concentric with the first mentioned cam and engageable substantially continuously by two of said projections while the said speed-varying member is not being moved by the oscillatable member and thereby lock said member from rotation, and having a low spot adapted for the passage of said projections one-by-one to permit of the rotary movement of the speed-varying member by the oscillatable member and prevent overrunning of the said member.
13. A variable speed mechanism constructed as set forth in claim 10 in which the rotary speed-varying member is formed with four ratchet teeth and four projections and the oscillatable member with two pawls adapted to engage the teeth.
14. In variable speed mechanism, the combination of a constant speed shaft; a rotary driven member; a carrying member secured to said shaft; a rotary speed-varying member journalled in said carrying member; gearing between said speed-varying member and the driven member; a cam disk journalled concentric with the constant speed shaft and geared thereto; an oscillatable member pivoted concentric with the speed-varying member and actuatable by said cam; pawl-and-ratchet driving means whereby a stepwise rotary movement may be imparted to the speed-varying means by rocking the oscillatable member; a plurality of equally spaced projections on the speed-varying member; a cam concentric with the first mentioned cam and engageable substantially continuously by two of said projections while the said speed-varying member is not being moved by the oscillatable member and thereby lock said member from rotation; and means adapted to check the momentum of the speed-varying member to prevent it overrunning the pawl-and-ratchet drive.
15. In variable speed mechanism, the combination of a constant speed shaft; a rotary driven member concentric with the shaft; a carrying member secured to said shaft; a rotary speed-varying member journalled in said carrying member; gearing between said speed-varying member and the driven member; rotary actuating mechanism for the speed-varying member geared to the constant speed shaft; and means for varying the gear ratio of the gearing between the constant speed shaft and the said rotary actuating mechanism for the speed varying member comprising a gear carrying frame mounted to swing concentric with the axis of the constant speed shaft and rotary driven member and carrying part of the gear train, a stationary member, fine-adjust-

ment mechanism between said member and the gear carrying frame adapted to finely adjust the meshing of the gears carried by the frame with the other gears of the train, and means for clamping the gear carrying frame and said member together.

16. Variable speed mechanism as set forth in claim 15 in which the fine-adjustment mechanism comprises a stud journaled in the member; a slide movable on the stud transversely thereof and pivotally connected with the gear carrying frame; and a screw threaded through the stud and rotatably connected with the frame to move the latter relative to the stud.

17. Variable speed mechanism as set forth in claim 15 in which the gear carrying frame is provided with an undercut groove and a gear is provided mounted on a stud having a head adapted to slide in said groove and to be clamped therein.

18. In variable speed mechanism, the combination of a constant speed shaft; a rotary driven member loose on the said shaft; a carrying member secured to said shaft; a spindle journaled therein; a speed-varying member secured to one end of said spindle; a gear wheel connected to the other end of said spindle; a rotatable member adapted to intermittently rotate said speed-varying member; means for actuating said rotatable member at a pre-determined speed relative to the constant speed shaft; a second carrying member rotarily adjustable relative to the first; two change-gear spindles journaled therein; a gear wheel adapted to be secured to either spindle, which gear in either of which positions is adapted by the adjustment of said second carrying member to be brought into mesh with the gear on the spindle of the speed varying member; and separate gear trains of different gear ratio whereby the rotary driven member may be driven from either of said change-gear spindles.

19. In variable speed mechanism, the combination of a constant speed shaft; a rotary driven member loose on the said shaft; a carrying member secured to said shaft; a spindle journaled therein; a speed-varying member secured to one end of said spindle; a gear wheel connected to the other end of said spindle; a rotatable member adapted to intermittently rotate said speed varying member; means for actuating said rotatable member at a pre-determined speed relative to the constant speed shaft; a second carrying member rotarily adjustable relative to the first; two change-gear spindles journaled therein; a gear wheel adapted to be secured to either spindle, which gear in either of which positions is adapted by the adjustment of said second carrying member to be brought into mesh with the gear on the spindle of the speed varying member; sep-

arate gear trains of different gear ratio whereby the rotary driven member may be driven from either of said change-gear spindles; an arm rotarily adjustable relative to the second carrying member; and a gear carried thereby adapted to be interposed between the gear on the spindle of the speed-varying member and a gear on one of the change-gear spindles.

20. In variable speed mechanism, the combination of a constant speed shaft; a rotary driven member loose on the said shaft; a carrying member secured to said shaft and comprising two spaced disks; a spindle journaled therein; a speed-varying member secured to one end of said spindle; a gear wheel connected to the other end of said spindle; a rotatable member adapted to intermittently rotate said speed varying member; means for actuating said rotatable member at a pre-determined speed relative to the constant speed shaft; a second carrying member rotarily adjustable relative to the first and comprising two spaced disks engaging the inner faces of the disks comprising said first carrying member; means for forcing the disks of said second carrying member against the adjacent faces of the first carrying member to clamp the carrying members together as adjusted; two change-gear spindles journaled therein; a gear wheel adapted to be secured to either spindle, which gear in either of which positions is adapted by the adjustment of said second carrying member to be brought into mesh with the gear on the spindle of the speed-varying member; and separate gear trains of different gear ratio whereby the rotary driven member may be driven from either of said change-gear spindles.

21. Variable speed mechanism constructed as set forth in claim 18 in which the second carrying member is provided with a spring actuated plunger and the first mentioned carrying member with a series of holes for engagement by the plunger to position the one relative to the other as desired.

22. In variable speed mechanism, the combination of a rotary driven member; a carrying member rotatably mounted; a speed-varying member journaled on said carrying member eccentric to the axis thereof; gearing between said speed-varying member and the driven member; a cam disk adjacent the carrying member; means for rotating the carrying member and for imparting a relative movement of rotation to the cam disk and carrying member; an oscillatable member journaled concentric with the speed-varying member and actuatable by said cam; pawl and ratchet-driving means whereby a stepwise rotary movement may be imparted to the speed-varying member by the rocking of the oscillatable member; means for positively locking said speed-varying member

while the said speed-varying member is not being moved by the oscillatable member; pawl and ratchet mechanism between the speed-varying member and the oscillatable member adapted to check the momentum of the speed-varying member to prevent it overrunning the pawl-and-ratchet drive; means on the carrying member for engaging said retaining ratchet to throw it into engagement at or about the time the rotary move-

ment of the speed-varying member commences; and means on the carrying member for engaging said retaining ratchet to throw it out of engagement at or about the time the rotary movement of the speed-varying member ceases. 15

Signed at Boston, Mass. this eleventh day of December, 1924.

J. HARRY WELLS.
